UNITED STATES PATENT OFFICE.

WILLIAM WALLACE WOTHERSPOON, OF NEW YORK, N. Y.

PNEUMATIC CONVEYING DEVICE.

1,116,862.

Specification of Letters Patent. Patented Nov. 10, 1914.

Application filed September 17, 1909, Serial No. 518,126. Renewed April 6, 1914. Serial No. 830,085.

To all whom it may concern:

Be it known that I, WILLIAM WALLACE WOTHERSPOON, a citizen of the United States, residing at New York, in the county of New York and State of New York, have invented certain new and useful Improvements in Pneumatic Conveying Devices, of which the following is a specification, reference being had therein to the accompanying drawing.

This invention relates to a pneumatic conveying device designed more particularly for discharging fine cargoes from vessels, and the invention consists of a tubular conveying body provided with suitable receiving and discharging openings and valves, in combination with controllable means for supplying air under pressure thereto; whereby by the manipulation of the valves and control of the pressure, the cargo may be caused to flow in either direction, thereby adapting the device either for the loading or unloading of a vessel.

The device is of such form and construction that it is portable in character, to adapt it to be employed in connection with wrecked vessels to discharge the cargo therefrom in order to facilitate the operation of the wreckers in raising the vessel. The device may, however, be built in as a permanent part of the vessel, or it may be used in any other manner as occasion may demand.

Referring to the drawings: Figure 1 represents a transverse section through a vessel, showing the conveying device applied thereto. Fig. 2 is a longitudinal section through the device on an enlarged scale. Fig. 3 is a transverse section on the line *a—a* of Fig. 1.

In the accompanying drawings: 1 represents a tubular body permanently closed at its lower end and having applied to its upper end a removable cap 2.

3 represents a receiving opening entering the side of the tubular body, and into which opening the cargo from the interior of the vessel is introduced previous to its discharge through the tubular body to the outside. This opening is closed by a hinged door 3^a, adapted to be locked tightly in closed position by means of a locking bolt 3^b, or by other appropriate means. 4 represents a second opening through the side of the tubular body for the discharge of the cargo into the vessel when loading, which opening is closed

by a door 4^a adapted to be locked tightly in closed position by a locking bolt 4^b, or other means.

5 represents a valve applied to the tubular body above the opening 3, and adapted to close the passage through the body at this point. This valve consists of a horizontal valve plate 5^a, slidable horizontally in a casing 5^b fixed to the tubular body, and provided with a valve stem 5^c, extending outwardly through a stuffing box 5^x in the valve case, the outer end of the stem having jointed to it a hand-lever 5^d, pivoted to the end of an arm 5^e projecting from the side of the body 1. By the operation of this handle 70 the valve may be slid in across the passage in the body, as shown in Fig. 3, thus closing said passage, or it may be slid outwardly free of said opening to leave the passage unobstructed at this point. 6 represents a similar valve applied to the body below the discharge opening 4. This valve consists of a valve plate 6^a, slidable horizontally in a valve casing 6^b, and adapted to be operated by the hand-lever 6^c pivoted to the tubular body 1, and jointed to a stem 6^d extending inwardly through the valve casing and connected at its inner end to the valve plate, so that by the operation of the lever the passage through the body 1 may be closed 85 or opened at this point as desired.

7 represents a pipe entering the upper end of the tubular body, through which pipe, air under pressure is introduced when the device is employed for loading the cargo 90 into the vessel. This pipe is provided with a cut-off valve 7^a for shutting off the supply of air. 8 represents a similar pipe entering the tubular body at its opposite end and below the valve 6, which pipe is for the introduction of air under pressure when the device is employed for discharging the cargo from the vessel, a valve 8^a being provided in the pipe to cut off the air pressure at this point when desired.

In the operation of the device it is suitably sustained in upright position in the vessel with the two openings 3 and 4 in the hold from which the cargo is to be discharged, or into which the cargo is to be loaded, and the end pipes 7 and 8 connected with a suitable source of air pressure, a compressor 9 being shown connected by pipes 10 and 11 with the pipes 7 and 8 respectively.

If the cargo within the vessel is to be dis-

100

105

110

charged, air valve 7^a is closed to shut off the air supply at the top of the body, and air valve 8^a opened to admit the air to the opposite end. Slide valve 6 is closed, slide valve 5 5 opened, cap 2 removed to open the upper end of the body, door 4^a closed, and door 3^a opened. Under this adjustment of the valves the air will be admitted beneath slide valve 6 under pressure. The cargo is then 10 shoveled, or otherwise introduced, through opening 3 and is piled up in the body on the valve plate 6^a, until it reaches the level of the opening 3. The door 3^a to this opening is then closed, and slide valve 6 quickly 15 opened, thus permitting the air to act on the mass of cargo in the tubular body, with the result that it will be driven by the air through the body and discharged through the open upper end of the same to the outside. Valve 6 is now closed again, and the 20 door 3^a opened to admit another charge of cargo to the interior of the body, and after this charge has been shoveled in, the foregoing operations are repeated, resulting in a 25 second discharge of cargo to the outside, and so on, the cargo being thus removed from the vessel by successive discharges, of portions of the same introduced into the tubular body through the receiving opening 3.

30 In the use of the device for loading cargo into the vessel, air valve 8^a is closed, slide valves 5 and 6 closed, door 3^a closed and door 4^a opened. Cap 2 is then removed and the cargo shoveled into the upper end of the 35 tubular body and piled up on the valve plate 5. The cap is then replaced and air valve 7^a opened to admit air above the mass of material supported on the valve plate. This valve is next quickly opened, with the result 40 that the air acting on the material will drive the same downward through the body and outwardly through opening 4 and into the hold of the vessel. The air valve 7^a is then closed again, valve 5 is also closed as before, 45 and cap 2 again removed. A second charge of cargo is then shoveled in, and the foregoing operations repeated, with the result that a second charge will be delivered to the ves-

sel, and so on, the cargo being thus loaded in by successive charges. 50

While I have shown and described my invention in its preferred form by way of example, it will be understood that the details may be variously modified and changed within the skill of the mechanic without departing from its limits, and it will be further understood that it is not limited to any particular form or embodiment except in so far as such limitations are specified in the claims. 55

Having thus described my invention, its construction and mode of operation, what I claim and desire to secure by Letters Patent of the United States is as follows:

1. In a pneumatic conveying device, the 65 combination of a tubular body provided with two openings each adapted to either receive or discharge material, independent closures for said openings, cut-off valves located respectively on opposite sides of one 70 of the openings, means for the admission of air under pressure at the outer side of one of the valves, and means for the admission of air under pressure at the outer side of the other of said valves; whereby the material 75 may be driven in either direction through the body.

2. A pneumatic conveying device comprising in combination, a tubular body closed at one end and open at the other end and provided with side openings, closures for said side openings, a cut-off valve between the closed end of the body and one of said side openings, a second cut-off valve between the other side opening and the open end of the 85 body, means for closing the latter at will, and means for introducing air under pressure to either end of the tubular body as desired. 80

In testimony whereof I affix my signature 90 in presence of two witnesses.

WILLIAM WALLACE WOTHERSPOON.
